UNITED STATES PATENT OFFICE.

CHARLES E. DATH, OF CHICAGO, ILLINOIS, ASSIGNOR TO WILLIAM H. MINER, OF CHICAGO, ILLINOIS.

UNDERFRAME FOR RAILWAY-CARS.

1,128,298.

Specification of Letters Patent. Patented Feb. 16, 1915.

Application filed March 4, 1914. Serial No. 822,338.

To all whom it may concern:

Be it known that I, CHARLES E. DATH, a citizen of the United States, residing at Chicago, in the county of Cook and State 5 of Illinois, have invented a certain new and useful Improvement in Underframes for Railway-Cars, of which the following is a full, clear, concise, and exact description, reference being had to the accompanying 10 drawings, forming a part of this specification.

My invention relates to improvement in underframes for railway-cars.

One object of my invention is to provide 15 a strong underframe for railway cars, and relates more particularly to the center-sills thereof.

A further object is to provide a center-sill construction that may be used as a re- 20 inforcing backbone for cars having wooden center-sills.

In the drawings forming a part of this specification, Figure 1 is a plan view of a portion of railway car and center-sills em- 25 bodying my invention; Fig. 2 is a side elevation of one of said sills partly in longitudinal section on line 2—2 of Fig. 1; Fig. 3 is a cross-section taken on line 3—3 of Fig. 2; Fig. 4 is a cross-section taken on line 4—4 of Fig. 2; and Fig. 5 is a cross-section taken on line 5—5 of Fig. 2.

Referring to the drawings, the numerals 6—6 represent wooden center-sills of an ordinary car-frame; 7 the end-sill; 8 the buffer-block secured thereto by the bolts 9—9; 35 10 the draw-bar carry-iron secured to the buffer-block by the bolts 11—11; 12—12 metal center-sills disposed on the inner faces of the wooden sills 6—6; the said 40 metal sills preferably comprising flat plates extending below the lower face of the wooden center-sills, the wooden center-sills resting upon the upper face 13 of the body-bolster 14, the metal sills 12 being pro- 45 vided with notches 15—15 underneath to receive the body-bolster transversely therein. At their ends the metal sills 12 are notched as indicated at the numeral 16 in Fig. 2 of the drawings to extend under the 50 end-sill and buffer-block. Throughout their length the metal center-sills are provided with the channel plate 17, riveted at its flanges 18—18 to the metal center-sills 12 by the rivets 19—19. Each metal center- 55 sill 12 is provided with short supporting

angle-irons 20, the vertical flange 21 of which is riveted to the sill 12 by the rivets 22—22, and the horizontal flange 23 thereof rests underneath the adjacent wooden sill 6 on both sides of the bolsters. Each metal center-sill is provided at its outer face with an angle-iron 24, extending longitudinally thereof, the vertical flange 25 of said angle-irons being riveted to the adjacent metal sill 12, and the horizontal flange thereof is 60 riveted at intervals to tie-plates 26—26 by means of the rivets 27—27. In front of the bolsters, in preferable construction one broad tie-plate 26 is provided extending from one metal sill to the other, and engaging at its rear edge 28 the front edge 29 of the lower forward flange of the body bolster. A tie-plate 26 is also provided immediately back of the body-bolster, the front edge 30 of which engages against the 75 rear edge 31 of the lower rear flange of the body-bolster. The said tie-plates immediately in front and in the rear of the body-bolster are preferably of considerable width to insure great strength at these points. On 80 the inner face of each metal sill 12 an angle-iron tie-piece 32 is provided, the same engaging the upper face 13 of the body-bolster, and being forwardly downwardly extended at a preferably sharp angle to the 85 lower edge of the metal sill to which it is secured, and each angle-iron tie-piece is rearwardly downwardly extended to the lower edge of the metal sill upon which it is mounted, each of said angle-irons being se- 90 cured to its appropriate sill by the rivets 34—34. The metal sills 12—12 are secured to the wooden sills 6—6 by bolts 35—35.

It will be apparent that the structure herein described is one of great strength and 95 rigidity, and that the same may be readily employed as a unitary structure in connection with cars having wooden center-sill by lifting the car-body from the bolster and placing the backbone structure described in 100 position between the wooden center-sill securing the same thereto, and placing the body-bolsters in the slots in the metal sills provided therefor.

I claim:

1. In an underframe for railway cars, the combination with wooden center-sills, of metal plate center-sills secured to the inner sides of the wooden sills and extending from end to end of the car, a channel mounted 110

- between and secured to the inner sides of said metal sills and extending from end to end of the car and angles along the lower edges of said metal sills.
5. In an underframe for railway cars, in combination, wooden center-sills, metal center-sills secured thereto and depending therefrom, said metal center-sills being provided with transverse slots to receive a body-bolster, angle-irons secured to the outer faces of the metal center-sills and engaging the under faces of the wooden center-sills, angle-irons secured to the outer lower faces of the metal center-sills, and a plurality of tie-plates connecting said last mentioned angle-irons.
10. In an underframe for railway cars, in combination, wooden center-sills, metal center-sills secured thereto and depending therefrom, a body-bolster, a channel-plate, angle-irons and tie-plates, the channel plate being secured to the metal center-sills along their upper edges and the angle irons to the inner faces thereof, said angle irons passing over the body bolster, and the metal center-sills being provided with transverse slots to receive the body-bolster, the tie-plates being looped over the body-bolster and secured to the metal center-sills.
15. In an underframe for railway cars, in combination, wooden center-sills, metal center-sills secured thereto and depending therefrom, a body-bolster, a channel-plate and tie-plates, the channel-plate being secured to the metal center-sills along their upper edges, the metal center-sills being provided with transverse slots to receive the body-bolster, the tie-plates being looped over the body-bolster and secured to the metal center-sills, and angle irons secured to the outer faces of the metal center-sills and engaging the lower edges of the wooden center-sills.
20. In an underframe for railway cars, in combination, wooden center-sills and metal center-sills secured thereto and depending therefrom, body-bolsters and transverse slots in the under edges of the metal center-sills to receive the body-bolsters, tie-loops secured to the metal center-sills and extending over the body-bolsters, a channel-plate secured between the metal center-sills at their upper edges, angle-irons between the body-bolsters secured to the outer faces of the metal center-sills and engaging the lower edges of the wooden center-sills, angle-irons secured to the outer lower faces of the metal center-sills and a plurality of tie-plates joining said angle-irons.
25. In an underframe for railway cars, in combination, wooden center-sills and metal center-sills secured thereto and depending therefrom, body-bolsters and transverse slots in the under edges of the metal center-sills to receive the body-bolsters, tie-loops secured to the metal center-sills and extending over the body-bolster, a channel-plate secured between the metal center-sills at their upper edges, angle-irons between the body-bolsters secured to the outer faces of the metal center-sills and engaging the lower edges of the wooden center-sills, angle-irons secured to the outer lower faces of the metal center-sills and a plurality of tie-plates joining said angle-irons, one of said tie-plates engaging the forward lower flange of the body-bolster, and the other of said tie-plates engaging the rear lower flange of the body-bolster.
30. In an underframe for railway cars, in combination, wooden center-sills, metal center-sills secured thereto and depending therefrom, a body-bolster, a channel-plate and tie-plates, the channel-plate being secured to the metal center-sills along their upper edges, the metal center-sills being provided with transverse slots to receive the body-bolster, the tie-plates being looped over the body-bolster and secured to the metal center-sills, and angle irons secured to the outer faces of the metal center-sills and engaging the lower edges of the wooden center-sills.
35. In an underframe for railway cars, in combination, wooden center-sills and metal center-sills secured thereto and depending therefrom, body-bolsters and transverse slots in the under edges of the metal center-sills to receive the body-bolsters, tie-loops secured to the metal center-sills and extending over the body-bolster, a channel-plate secured between the metal center-sills at their upper edges, angle-irons between the body-bolsters secured to the outer faces of the metal center-sills and engaging the lower edges of the wooden center-sills, angle-irons secured to the outer lower faces of the metal center-sills and a plurality of tie-plates joining said angle-irons, one of said tie-plates engaging the forward lower flange of the body-bolster, and the other of said tie-plates engaging the rear lower flange of the body-bolster.
40. In an underframe for railway cars, in combination, wooden center-sills and metal center-sills secured thereto and depending therefrom, body-bolsters and transverse slots in the under edges of the metal center-sills to receive the body-bolsters, tie-loops secured to the metal center-sills and extending over the body-bolster, a channel-plate secured between the metal center-sills at their upper edges, angle-irons between the body-bolsters secured to the outer faces of the metal center-sills and engaging the lower edges of the wooden center-sills, angle-irons secured to the outer lower faces of the metal center-sills and a plurality of tie-plates joining said angle-irons, one of said tie-plates engaging the forward lower flange of the body-bolster, and the other of said tie-plates engaging the rear lower flange of the body-bolster.
45. In an underframe for railway cars, in combination, wooden center-sills, metal center-sills secured thereto and depending therefrom, a body bolster, a channel-plate and tie-plates, the channel plate being secured to the metal center-sills along their upper edges, the metal center-sills being provided with transverse slots to receive the body-bolster, the tie-plates being looped over the body-bolster and secured to the metal center-sills, and angle irons secured to the outer faces of the metal center-sills and engaging the lower edges of the wooden center-sills.
50. In an underframe for railway cars, in combination, wooden center-sills and metal center-sills secured thereto and depending therefrom, body-bolsters and transverse slots in the under edges of the metal center-sills to receive the body-bolsters, tie-loops secured to the metal center-sills and extending over the body-bolster, a channel-plate secured between the metal center-sills at their upper edges, angle-irons between the body-bolsters secured to the outer faces of the metal center-sills and engaging the lower edges of the wooden center-sills, angle-irons secured to the outer lower faces of the metal center-sills and a plurality of tie-plates joining said angle-irons, one of said tie-plates engaging the forward lower flange of the body-bolster, and the other of said tie-plates engaging the rear lower flange of the body-bolster.

CHARLES E. DATH.
